(71) **Applicant:** **M3 Accounting Services, Inc.**, Gainesville, GA (US)

Primary Examiner — Cathron C Brooks

(72) **Inventor:** **John Bingham McKibbon, III**, Gainesville, GA (US)

Assistant Examiner — Ian F Whitmore

(73) **Assignee:** **M3 Accounting Services, Inc.**, Gainesville, GA (US)

(74) *Attorney, Agent, or Firm* — Thomas | Horstemeyer, LLP

(**) **Term:** **15 Years**

CLAIM

(21) **Appl. No.:** **29/624,296**

I claim the ornamental design for a display screen, or portion thereof, with a graphical user interface component, as shown and described.

(22) **Filed:** **Oct. 31, 2017**

DESCRIPTION

(51) **LOC (12) Cl.** **14-04**

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

(52) **U.S. Cl.**

This application is related to U.S. patent application Ser. No. 29/624,287, entitled “Display Screen, or Portion Thereof, With a Transitional Graphical User Interface Component,” filed on Oct. 31, 2017, and U.S. patent application Ser. No. 29/624,292, entitled “Display Screen, or Portion Thereof, With a Transitional Graphical User Interface Component,” filed on Oct. 31, 2017, the contents of which being incorporated by reference in their entirety herein.

(53) **USPC** **D14/486**

The file of this patent contains at least one drawing or photograph executed in color. Copies of this patent with color drawing(s) or photograph(s) will be provided by the Office upon request and payment of the necessary fee.

(58) **Field of Classification Search**

The FIGURE is a front view of a display screen or portion thereof with a graphical user interface component, showing the new design.

USPC D14/485-495; D20/10, 11, 22-33, 39,
D20/40

The broken lines illustrate a display screen or portion thereof and form no part of the claimed design.
